UNITED STATES PATENT OFFICE.

ORVILLE E. MURPHY, OF SEMINOLE, OKLAHOMA, ASSIGNOR OF FORTY-NINE PER CENT TO AMERICAN IRON & MACHINE WORKS, INC., OF OKLAHOMA CITY, OKLAHOMA, A CORPORATION OF OKLAHOMA.

ROTARY WELL DRILL.

Application filed March 1, 1927. Serial No. 171,836.

This invention relates to rotary well drills and more particularly to rotary well drills employing diametrically-aligned cutting rollers and having a centrally disposed water course, such as is illustrated in the patent to H. W. Fletcher, granted February 5, 1924, No. 1,482,787.

In the patent above mentioned is illustrated a rock bit having a recess in its bottom within which are located a pair of diametrically opposed rollers which perform the actual drilling operation. In the center of the bit, there is a removable water course, by means of which flushing water or slush 15 is delivered at the bottom of the bit to remove from the hole the matter reduced by the rollers. By the construction ordinarily employed, this flushing water is delivered directly against the rollers of the bit, with 20 the result that it splashes outwardly against the walls of the bore and tends to cause the same to cave and to wear the same, so that a defective bore is produced, which must, at 25 times, be cemented before practical operation of the well can be obtained. Accordingly, an important object of this invention is to so improve the means for delivering the water to the bottom of the well that this water is directed against the bottom of the 30 bore and not against the rollers, so that it will be splashed against the walls.

A further object of the invention is to produce a device of this character which may be applied to bits now in use without 35 in any manner altering the construction of the bit proper.

These and other objects I attain by the construction shown in the accompanying drawings, wherein for the purpose of illustration is shown a preferred embodiment of 40 my invention and wherein:—

Figure 1 is a vertical sectional view through a drill embodying a water course constructed in accordance with my invention;

Figure 2 is a bottom plan view of the drill;

Figure 3 is a detail sectional view showing a modified method of connecting the 50 sections of the water course.

Referring now more particularly to the drawings, the numeral 10 generally designates a rock bit of a well known type. This rock bit is diametrically divided to

form two separable sections 11 and 12 held in assembled relation by a bolt 13. The bottom faces 14 of the sections diverge downwardly and are each provided with a mounting 15 for a roller 16. Adjacent faces of the sections are provided with longitudinally extending recesses 17 combining to produce a channel, for the reception of a removable water course, generally designated at 18. This channel is enlarged intermediate its ends, as indicated at 19, the lower end of the enlargement extending adjacent the lower end of the channel.

Between the upper faces or peripheral portions of the bit, rollers 16 and the inclined walls 14, a substantially triangular space 20 is produced and in accordance with my invention, the lower end of the removable water course 18 is provided with a hollow T-head 21 fitting within this space and extending outwardly toward the sides 75 of the bit. The ends 24 of the T-head are closed and one of the apices 25 of this head is upwardly extended. The base or bottom wall 26 of the T-head is provided beneath the axis of the water course with a triangular lug 27 forming a baffle splitting the stream passing through the main portion of the water course and directing the flow toward the ends of the head. Adjacent its ends, this base 26 has formed there- 85 in downwardly directed openings 28, which direct the outgoing water downwardly into the space between the rollers 16, so that it will impinge directly upon the bottom of the hole. 90

Any suitable means may be provided for attaching the T-head 21 to the water course. In the present illustration, I have disclosed in Figure 1 a water course formed in two sections 18^a and 18^b, one of which fits the 95 lower portion of the channel produced by the recesses 17 and has an enlarged head fitting into the enlargement 19 of the channel and thus limiting its downward movement. The upper section 18^a fits into the 100 upper end of the channel and has its lower end extending into the upper end of the section 18^b. In Figure 3, this structure has been modified, the original water course being retained and the T-head 21 applied 105 thereto as an attachment. To this end, the T-head is provided with a tubular extension 29, the upper end of which is exteriorly

2
screw-threaded for engagement with screw threads formed upon the interior of the main water course 18.

Since the construction hereinbefore set forth is capable of a certain range of change and modification without materially departing from the spirit of the invention, I do not limit myself to such specific structure except as hereinafter claimed.

10 I claim:

1. The combination with a rotary well drill having substantially diametrically aligned cutting rollers at its lower end and having a water course extending axially of the drill normally delivering flushing water to the lower end thereof, of a T-head applied to said water course having means dividing flushing fluid delivered therethrough into two downwardly directed streams clearing said rollers.

2. The combination with a rotary well drill having a substantially V-shaped notch in its bottom the walls of which have opposed cutting rollers mounted thereon, of a transversely extending conduit having closed ends removably mounted at the apex of the V-shaped notch and having in its base downwardly directed openings for delivering flushing water downwardly at opposite sides of the rollers and means for delivering flushing water to said conduit at the center thereof.

3. The combination with a rotary well drill having a pair of cutting rollers at its opposite ends and a water course normally delivering water to the lower end of the drill axially of the drill, of means receiving the water from the water course and deflecting it outwardly beyond the sides of the rollers and then directing it downwardly.

4. The combination with a rotary well drill having a substantially V-shaped notch in its bottom the walls of which have opposed cutting rollers mounted thereon and a transversely extending triangular conduit having closed ends and having an apex

thereof extended into the apex of the V-shaped notch, said conduit having in its base openings spaced longitudinally of the conduit from the center thereof and means for delivering flushing water to said conduit at the center thereof.

5. In combination, a rotary well drill formed in two separable sections combining in assembled relation to produce at the bottom of the drill a V-shaped notch and at the axis of the drill a channel opening into said notch, opposed cutting rollers mounted upon the walls of the V-shaped notch, a conduit extending into and fitting in the apex of the V-shaped notch and having an intake extending upwardly into said channel, discharge openings in said conduit at points spaced transversely of the drill and longitudinally of the conduit from the axis of the drill and a removable water course in said channel discharging into the intake of said conduit.

6. In combination, a rotary well drill formed in two separable sections combining in assembled relation to produce at the bottom of the drill a V-shaped notch and at the axis of the drill a channel opening into said notch, opposed cutting rollers mounted upon the walls of the V-shaped notch, a conduit extending into and fitting in the apex of the V-shaped notch and having an intake extending upwardly into said channel, discharge openings in said conduit at points spaced transversely of the drill and longitudinally of the conduit from the axis of the drill and a removable water course in said channel discharging into the intake of said conduit, said channel being enlarged intermediate its ends, said intake having at its upper end an enlargement fitting in the enlargement of the channel and receiving the lower end of the removable water course.

In testimony whereof I hereunto affix my signature.

ORVILLE E. MURPHY.
